UNITED STATES PATENT OFFICE.

AXEL C. G. DREILICK, OF GOTTFENBORG, SWEDEN, ASSIGNOR TO ERNST J. OHNELL,
TRUSTEE.

CHART OR MAP HOLDER.

1,249,352.

Specification of Letters Patent. Patented Dec. 11, 1917.

Application filed December 16, 1916. Serial No. 137,309.

To all whom it may concern:

Be it known that I, AXEL C. G. DREILICK, a subject of the King of Sweden, and resident of Gottenborg, Sweden, have invented 5 certain new and useful Improvements in Chart or Map Holders, of which the following is a specification.

The present invention relates to chart or map holders.

10 The object of the invention is to provide a very simple and convenient arrangement for holding large sheets, such as maps, charts, drawings and the like in convenient position for reading, and while the device 15 is especially useful on shipboard for holding mariners' charts, it is nevertheless adapted for various other uses. The device consists primarily of a plurality of arms or supports hinged or arranged to rock from 20 a support, the arms being adapted to rest upon a table, desk or other support to act as weights to hold the unrolled portion of a drawing, chart or map on the table, the 25 supports having curved ends to form supporting members for the rolled portion of the map, chart or drawing.

In the drawings forming part of this application

30 Figure 1 is a perspective view of my invention associated with a table;

Fig. 2 is a side elevation thereof with a portion broken away, showing the rods raised to an inoperative position;

Fig. 3 is a detail view showing a method 35 of connecting the supporting shaft to a wall;

Fig. 4 is a sectional view taken on the line 4, 4, of Fig. 1;

Fig. 5 is a side elevation of the device 40 showing a chart in position for use, and

Fig. 6 is a plan view thereof.

The charts used by mariners are generally 45 large and bulky and in order to follow the various readings, it is customary to place the chart upon a table and to allow the rolled portion to fall on the floor, owing to the fact that the table is seldom large enough to accommodate the whole chart. This has often resulted in the chart becoming torn or 50 mutilated and the present device is intended to provide a convenient arrangement for holding flat the unrolled portion of the chart which is being read and for holding the rolled portion.

55 In the drawings I have shown brackets 1

attached to a wall 2; and mounted in these brackets there is a shaft 3. Near the ends of this shaft there are curved arms 4 having looped ends 5 loosely fitting the shaft so that the arms may be adjusted therealong. Each 60 arm is offset at 6 and the horizontal portion 7 is adapted to lie parallel with and rest upon a suitable support such as a table 8.

In a preferred construction the rods 4 are made extensible and for this purpose I have 65 shown the member 7 formed of tubular cross section as shown in Fig. 4, the tubular portion receiving the member 9 which slides freely within this tubular portion of the member 7. The member 9 is curved into 70 loop shape at 10 the loop turning downwardly. This construction is the same for both of the members 4.

In using the device the rods 4 are arranged in the position shown in Fig. 2, in which 75 position the spring clips 11 engage the members 7 and hold them close to the wall. The sheet, such as a chart or map is partially unrolled and arranged across the table top 8, so that the rolled portion is at the forward 80 edge of the table, as viewed in Fig. 1. The rods are then lowered upon the table and upon the drawing or chart near the side edges of the latter, and the roll 12 is placed 85 in the curved loops 10 of the rods, as shown in Figs. 5 and 6. In this condition the portion 13 of the chart or map which is being read is held flat and smooth upon the table and the rolled portion is conveniently held 90 so that it will not drag on the unrolled portion nor fall on the floor. If it is desired to read farther down on the chart or map the chart is further unrolled by drawing on the top edge until the chart is sufficiently unrolled to expose the portion which is to be 95 read. No further handling is required for this operation other than drawing on the top edge of the chart or map. If the chart is drawn out to extend beyond the rear edge 100 of the table it may be allowed to hang down.

A method of exposing a more extended portion of the chart to view is to draw the rod members 9 outwardly from the members 7, the latter holding the chart upon the table 105 while the roll 12 is carried outwardly with the loops 10. This will form an extended support for the roll beyond the edge of the table, and instead of a portion equal to the depth of the table being exposed there will 110

be an additional portion of the chart displayed corresponding to the distance that the members 9 are extended. In the extended position the rods 4 and their loops 10 5 form a support for the roll 12 in the same manner as when the parts are in the position shown in Figs. 5 and 6. It will be obvious that the telescoping action is not limited to two members at each side, as the telescoping 10 action may be multiplied to allow for a greater extension of the parts.

The rods 4 may be slid along the shaft 3 to any desired positions, to adapt them to charts of different widths.

15 Having now described my invention what I claim is:—

1. A device of the class described comprising rods, and means for attaching them to a support in spaced relation, such as a 20 wall, whereby the rods may swing, said rods being adapted to rest upon a table or other support near the wall, whereby they will form weights for holding a sheet flat upon the table or other support adjacent to the 25 edges of the sheet, said rods having means on their outer ends adapted to receive and support the rolled portion of said sheet, for the purpose set forth.

2. A device of the class described comprising rods, and means for attaching them to a support, such as a wall, whereby the rods may swing vertically, said rods being adapted to rest upon a table or other support near the wall, whereby they will form 30 weights for holding a sheet flat upon the table, said rods being curved at their outer 35

ends downwardly and backwardly to form open loops to receive the rolled portion of said sheet and to support the same beyond the edge of said table.

3. A device of the class described comprising rods and means for attaching them to a support in spaced relation, such as a wall, whereby the rods may swing, said rods being offset below their axis and being 40 adapted to rest upon a table or other support near the wall, whereby they will form weights for holding a sheet flat upon the table adjacent the edges of the sheet, said rods having their outer ends formed into open 45 loops adapted to receive and support the rolled portion of said sheet.

4. A device of the class described comprising rods and means for attaching them to a support, such as a wall, whereby the 50 rods may swing, said rods being adapted to rest upon a table or other support near the wall, whereby they will form weights for holding a sheet flat upon the table, said rods including extensible members whereby the 55 rods may be extended in the direction of their length, said extensible members having open loops at their free ends adapted to receive and support the rolled portion of said sheet.

Signed at New York city, in the county of New York, and State of New York, this 11th day of December, A. D. 1916.

AXEL C. G. DREILICK.
